UNITED STATES PATENT OFFICE.

HENRY M. NAGLEE, OF THE UNITED STATES ARMY.

IMPROVEMENT IN APPARATUS FOR DETECTING AND EXPLODING SUBMARINE TORPEDOES.

Specification forming part of Letters Patent No. 39,162, dated July 7, 1863.

To all whom it may concern:

Be it known that I, HENRY M. NAGLEE, brigadier-general of the United States Army, have invented certain apparatus for Finding and Destroying Torpedoes; and I do hereby declare the following to be a full, clear, and exact description of the same, reference being had to the accompanying drawing, and to the letters of reference marked thereon.

My invention consists in searching for and exploding torpedoes by means of a raft or other suitable object permitted to float with the tide or current from a vessel at anchor, and having the appliances herein described or their equivalent to be operated from the deck of the said vessel, the said appliances being such as to cut, catch, seize, or become entangled with the discharging cord of the torpedoes, the explosion of which is effected without danger to the vessel or to the operators with the apparatus.

In order to enable others to make and use my invention, I will now proceed to describe the manner of carrying it into effect.

On reference to the accompanying drawings, which form a part of this specification, Figure 1 is a side view of my apparatus for finding and destroying torpedoes; Fig. 2, an end view; Fig. 3, a plan thereof; Fig. 4, part of the apparatus drawn to an enlarged scale; Fig. 5, a diagram illustrating the operation of my invention, and Fig. 6 a modification of the apparatus.

Similar letters refer to similar parts throughout the several views.

A is a light raft, composed in the present instance of two simple logs, *a* and *a'*, arranged a short distance apart from each other and connected together by cross-pieces *b* *b'*, or lashed to each other in any manner which may be deemed most appropriate. In place of these logs an ordinary boat may be used, or two boats secured to each other; in fact, any object having the desired buoyancy will serve the required purpose. To this raft is attached (at the point *x*) a light piece, *B*, of wood, forming a lever, one arm of which is of such a length that when occupying the angular position shown in Fig. 1 the lower end of the lever will reach to within a short distance from the bottom of the river, harbor, or creek in which the torpedoes are supposed to be

anchored. To the end of the upper or short arm of the lever is connected a light rope or cord, *G*, which passes under a pulley, *w*, or through an eye situated at the rear of the raft, and thence to the monitor or other vessel from which the raft is permitted to float. To the front of the long arm of the lever *B* are secured a short distance apart from each other the appliances best understood by reference to the enlarged view, Fig. 4. Each of these appliances consists of a metal plate, *H*, secured to the lever *B* by a screw, *h*, or otherwise, but situated a short distance from the lever. To the end of each plate a pawl, *i*, is loosely hinged, the end of each pawl bearing, owing to its gravity, against the lever, or being lightly forced against the same by a suitable spring.

In order that the operation of my invention may be thoroughly understood, it will be necessary to explain the arrangement of the torpedoes which my apparatus is intended to find and destroy.

The torpedoes hitherto used by the enemy consist of iron vessels *K* and *K'* of the form seen in Fig. 2, the vessels being charged with explosive material. They are connected together by a cord or wire, *t*, the pulling of which will cause their explosion. They are anchored and are permitted to float so far above the bottom that the cord will reach the keel of a vessel passing through the channel in which the torpedoes are placed.

The operation of my invention will be best understood by reference to Fig. 5, in which *M* represents a monitor or other vessel anchored at *y* in the channel of a river or harbor through which it is necessary for a vessel to pass and in which the torpedoes are supposed to be anchored, the tide flowing in the direction of the arrow. The raft with its lever is in the first instance permitted to float with the tide in the direction of the line *m*. Should the lever come in contact with the cord *t* which connects the torpedoes together, the movement of the raft will be arrested, which will indicate that some of the torpedoes have been found, and that it is time to pull the rope or cord *G*, and thereby raise the long arm of the lever *B*. The cord *t* of the torpedo must necessarily become fastened in one of the plates *H*, either by passing upward in the direction

of the arrow 2, Fig. 4, when the lever first comes in contact with the cord, or by passing downward in the direction of the arrow 3, Fig. 4, when the long arm of the lever is raised. In either case the cord connecting the torpedoes, owing to the pawls *i i*, is retained by the lever and is necessarily pulled, and the torpedo consequently explodes. It should be understood that the monitor *M* is anchored at such a distance from the torpedoes that the explosion can have no injurious effect upon it.

The channel may be searched for any length by permitting the raft with its lever to float in the direction of the line *m*, after which the rope or cord *G* may be moved to the opposite side of the monitor and the raft be permitted to float in the direction of the dotted line *n*, so that the search for the torpedoes may be continued in the course indicated by that line, and the raft may be caused to float in other courses by securing to the monitor a pole projecting a considerable distance from one side or the other of the vessel, and permitting the raft to float from the outer end of the pole. The raft may be made to take a still wider range by the rudder, which acted upon by a strong tide or current will cause the monitor to assume the positions illustrated by dotted lines, thereby permitting the raft to take the courses pointed out by the dotted lines *p* and *q*. Thus the channel can be searched and rendered clear of torpedoes to a width sufficient to permit any vessel to pass with safety and without danger to the vessel from which the operations are conducted.

In some instances it may be desirable to cut the rope which connects the torpedoes, in

which case the lever *B* may be provided with a knife or other severing apparatus.

In the modification illustrated in Fig. 6 the lever *B* is shorter than that described in reference to Fig. 1, and to the submerged end of the lever is attached a weighted rope or chain to which are secured a number of hooks, the end of the rope or chain being permitted to drag on the bottom of the river or harbor, so that some of the hooks would be certain to catch the cord *t* of any torpedoes anchored in the course along which the raft is permitted to float.

I claim as my invention and desire to secure by Letters Patent—

1. Searching for and exploding torpedoes by means of a raft, *A*, or other suitable object permitted to float with the tide or current from a vessel at anchor, and having the appliances herein described or their equivalent, to be operated from the deck of the said vessel, the said appliances being such as to cut, or to catch, seize, or become entangled with the discharging cords of the torpedoes, as herein set forth.

2. The lever *B*, its plates *H*, and pawls *i*, or other similar appliances, the whole being attached to the raft *A* or other floating object, and the lever being controlled by a cord or rope, *G*, communicating with the vessel *M*, all substantially as set forth, for the purpose specified.

In testimony whereof I have signed my name to this specification in the presence of two subscribing witnesses.
